[57] CLAIM

The ornamental design for a combination can opener and blender assembly, as shown and described.

DESCRIPTION

FIG. 1 is a front elevational view of a combination can opener and blender assembly showing my new design;

FIG. 2 is a rear elevational view thereof;

FIG. 3 is a bottom plan view thereof;

FIG. 4 is a top plan view thereof;

FIG. 5 is a right side elevational view thereof;

FIG. 6 is a front elevational view thereof, with the configuration for blender operation shown;

FIG. 7 is a rear elevational view of that shown in FIG. 6;

FIG. 8 is a bottom plan view of that shown in FIG. 6;

FIG. 9 is a top plan view of that shown in FIG. 6;

FIG. 10 is a right side elevational view of that shown in FIG. 6;

FIG. 11 is a front elevational view of that shown in FIG. 1, shown removed from the support brackets for illustrative purposes;

FIG. 12 is a rear elevational view of that shown in FIG. 11;

FIG. 13 is a bottom plan view of that shown in FIG. 11;

FIG. 14 is a top plan view of that shown in FIG. 11;

FIG. 15 is a front side elevational view of that shown in FIG. 11;

FIG. 16 is a top, front right side perspective view of that shown in FIG. 1; and

FIG. 17 is a bottom rear, right side perspective view of that shown in FIG. 1.

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 13.

FIG. 14.

FIG. 15.

FIG. 16.

FIG. 17.
